UNITED STATES PATENT OFFICE.

PETER MACCAFFRAY, OF PHILADELPHIA, PENNSYLVANIA, ASSIGNOR TO
THE E. H. GODSHALK COMPANY, OF PENNSYLVANIA.

DESIGN FOR A CURTAIN.

SPECIFICATION forming part of Design No. 32,101, dated January 9, 1900.

Application filed December 16, 1899. Serial No. 740,601. Term of patent 31 years.

To all whom it may concern:

Be it known that I, PETER MACCAFFRAY, a citizen of the United States, residing in the city and county of Philadelphia, State of Pennsylvania, have invented and produced a new and original Design for a Curtain, of which the following is a specification, reference being had to the accompanying drawing, forming part thereof.

The leading features of my design for a curtain are, first, a border of a group of flowers; next, a central portion composed of an arch of flowers with pointed figures radiating therefrom, and, finally, the upper portion composed of flowers with diverging and converging scrolls around the same.

The figure represents a face view of a piece of curtain embodying my design.

In the drawing, A designates the border, composed of the flowers B B and the scrolls C, grouped therewith.

D designates the central portion, the same being composed of the arch E and the pointed figure F, radiating inwardly therefrom, said arch inclosing the top flowers of the border. 25

G designates the upper portion, composed of the flowers H, the diverging scrolls J below, and the converging scrolls K above, said flowers H being within said scrolls J K.

Rising from the base of the arch E are the 30 columns L and M of flowers and scrolls, the same joining the scrolls J K.

Having thus described my invention, what I claim as new, and desire to secure by Letters Patent, is—

The design for a curtain substantially as shown and described. 35

PETER MACCAFFRAY.
